E. M. HOWG.
LATCH FOR CHAINS.
APPLICATION FILED SEPT. 9, 1921.

Patented June 13, 1922.

Inventor:
E. M. Howg.

Eccleston & Eccleston.

Atty's.

UNITED STATES PATENT OFFICE.

EDWIN M. HOWG, OF LENNOX, SOUTH DAKOTA.

LATCH FOR CHAINS.

1,419,565.

Specification of Letters Patent. Patented June 13, 1922.

Application filed September 9, 1921. Serial No. 499,417.

To all whom it may concern:

Be it known that I, EDWIN M. HOWG, a citizen of the United States, residing at Lennox, in the county of Lincoln and State 5 of South Dakota, have invented certain new and useful Improvements in Latches for Chains, of which the following is a full, clear, and exact description.

My invention relates to latches for chains, 10 and more particularly to a latch or lever for locking non-skid chains on automobile tires, and has for its object to provide novel means for securing the latch or lever in locking position.

15 A further object of the invention is to so form the latch that the pull of the chain thereon will tend to hold the latch in closed position rather than tend to open it.

Other objects and advantages of the invention will be apparent from the following 20 description when taken in connection with the accompanying drawing, in which,

Figure 1 is an elevation of the chain showing the latch about to be moved to 25 locking position.

Figure 2 is a view similar to Figure 1, the latch being shown in locked position, and

Figure 3 is a side elevation of the latch 30 removed from the chain.

Referring to the drawing more in detail, the numeral 1 designates a chain of any type although my invention is intended more especially to be used in connection 35 with the longitudinally extending chains of non-skid chains which encircle the wheels of automobiles. Pivoted to one of the links 2 of the chain, preferably the end link, is the latch 3, which is substantially hook-shaped, and has its longer arm 4 bent into 40 the form of a spiral 5. The spiral 5 terminates in the finger 6.

The latch 3 is also provided with the inclined notch or passageway 7 which terminates at or slightly beyond the pivot 45 point of the latch. By having the notch 7 located in the manner shown, the pull of the chain is along the line of the pivot and thereby will not tend to throw the latch 50 open or distort the same.

In securing the latch in position the arm 4 is extended through the desired link, as shown in Figure 1 of the drawing, the latch is then swung on its pivot to the position shown in Figure 2. The link 8 is then 55 manipulated to such positions that the spiral will encircle it and thereby lock the latch in position. By having the finger 6 somewhat elongated danger of the spiral becoming detached is completely eliminated. 60

Having fully described my invention, what I claim as new and desire to secure by Letters Patent is:

1. In a non-skid chain for tires, a chain, 65 a latch comprising a hook-shaped member connected thereto, and a spiral formation on one arm of said hook-shaped member, said spiral extending through at least 360°, relative movement of the chain links permitting co-operative engagement of the 70 spiral formation and one of the links.

2. In a non-skid chain for tires, a chain, 75 a latch comprising a hook-shaped member connected thereto, and a spiral formation on one end of said hook-shaped member, said spiral extending through at least 360°, relative movement of the chain links permitting co-operative engagement of the 80 spiral formation and one of the links.

3. The combination with a chain of a 85 hook-shaped member pivoted to one end of the chain, the longer arm of the hook-shaped member being adapted to extend through a link of the other end of the chain, and a spiral formation on said arm for engaging a portion of the chain, said spiral extending through at least 360°, relative movement of the chain links permitting co-operative engagement of the spiral 90 formation and one of the links.

4. The combination with a chain of a hook-shaped member pivoted to one end of the chain, the longer arm of the hook-shaped member being adapted to extend through a link of the other end of the 95 chain, the passageway between the arms of the hook-shaped member being inclined so that it terminates in line with the pivot and the end of the longer arm.

EDWIN M. HOWG.
